No. 37,150.

Patented September 20, 1904.

UNITED STATES PATENT OFFICE.

CHARLES GAY, OF NEW HAVEN, CONNECTICUT.

DESIGN FOR A CHAPLET OR SHRINE OF THE HOLY ROSARY.

SPECIFICATION forming part of Design No. 37,150, dated September 20, 1904.

Application filed June 15, 1904. Serial No. 212,732. Term of patent 14 years.

To all whom it may concern:

Be it known that I, CHARLES GAY, a citizen of the United States, and a resident of New Haven, in the county of New Haven and State of Connecticut, have invented a new, original, and ornamental Design for a Chaplet or Shrine of the Holy Rosary, reference being had to the accompanying drawing, in which the figure is a perspective view of the chaplet or shrine of the holy rosary, showing my design.

I claim as new and desire to secure by Letters Patent—

The ornamental design for a chaplet or shrine of the holy rosary herein shown.

CHARLES GAY.
